(57) **CLAIM**

The ornamental design for a “stand for a video monitor,” as shown and described.

DESCRIPTION

FIG. 1 is a top, front and right side perspective view of a stand for a video monitor according to my design;

FIG. 2 is a front elevational view thereof;

FIG. 3 is a rear elevational view thereof;

FIG. 4 is a bottom plan view thereof;

FIG. 5 is a top plan view thereof; and,

FIG. 6 is a right side view, the left side being a mirror image thereof.

1 Claim, 3 Drawing Sheets
